UNITED STATES PATENT OFFICE.

GEORGE W. SWIFT, JR., OF BORDENTOWN, NEW JERSEY.

BINDING AND HEADING BAND FOR BARRELS, BOXES, AND THE LIKE.

1,307,765.

Specification of Letters Patent. Patented June 24, 1919.

Application filed December 4, 1918. Serial No. 265,223.

To all whom it may concern:

Be it known that I, GEORGE W. SWIFT, Jr., a citizen of the United States, residing at Bordentown, county of Burlington, State 5 of New Jersey, have invented certain new and useful Improvements in Binding and Heading Bands for Barrels, Boxes, and the like, of which the following is a specification.

10 The purpose of the present invention is to produce a simple and effective metal binding band for securing the head in the end of a barrel, box or other closure, and to this end I have produced a binding and heading band formed from a single integral piece of sheet metal with an inwardly presented channel or groove to receive the closure head, and a downwardly presented channel or groove to fit over the edge of the closure. 15 The binding and heading bands for circular closures, such as barrels, tubs, etc., are preferably made in the form of split hoops having the head and body engaging channels or grooves referred to. The bands 20 for heading rectangular or other shaped closures, can be made up of a proper number of short, straight strips to properly fit the straight walls of the closure, or a continuous strip for the entire angular top 25 edge of the closure walls may be used, in which latter case, the binding strip will be properly bent to fit around the wall angles. 30 When applying the improved binding band, it is first compressed around the closure head and fastened thereon by brads or other suitable means so that the flanged and grooved band will constitute a channeled heading surrounding the head. The 35 attached head and channeled band will then be applied to the open end of the closure, the head fitting snugly in the open end of the closure, while the depending outer flange will snugly surround the top of the closure walls. Any suitable means may be 40 employed for fastening the binding band to the closure, but I prefer to employ brads or nails which will pass through the flange and closure walls into the head. 45

In order that my invention may be fully 50 understood, I will first describe the same with reference to the accompanying drawings and after point out the novelty more particularly in the annexed claims.

In said drawings:

55 Figure 1 is a perspective view of the im-

proved binding band in the form of a barrel heading hoop;

Fig. 2 is a detail sectional view showing an attached barrel head and hoop supported adjacent to the chime of a barrel; 60

Fig. 3 is a similar view showing the head and hoop secured in position upon the barrel;

Fig. 4 is a side elevation of a completely headed barrel; 65

Fig. 5 is a detail sectional plan view taken on the line 5—5 of Fig. 4, having a part of the head broken away;

Fig. 6 is an enlarged detail sectional perspective view, of part of a binding hoop attached to a barrel head; 70

Fig. 7 is detail side elevation of part of a barrel binding hoop;

Fig. 8 is a detail perspective view of part of a rectangular closure or box bound and 75 headed with the improved band;

Fig. 9 is a detail perspective of the detached band;

Figs. 10 and 11 are detail views of a further modification. 80

The improved binding and heading band has been designed primarily to secure the heads in paper and other forms of veneer barrels and boxes which are now coming largely into use. The primary form of the 85 improved band is used for circular closures such as barrels, tubs and cylindrical boxes, but other forms of the invention are applicable to other forms of boxes.

In Figs. 1 to 7 of the drawings, the barrel 1 is shown of cylindrical form with ordinary strengthening bands or hoops 2 surrounding its central zone and the improved binding and heading bands in the form of hoops 5 at the opposite ends. These heading hoops will 95 now be described.

The binding and heading hoops 5 are made in flanged ring form, split, as shown at 6 in Fig. 1, of a single integral piece of sheet metal shaped by suitable bending processes. 100

The hoops 5, of a general circular contour to fit a barrel, have an outer annular lip 6, an annular binding edge 7, an inner circular wall 8 forming with the lip 6 an annular recess or channel 9 to receive the chime of the open end of the barrel. The wall 8 connects through an obtuse angle with an inwardly inclined wall 10, joined through an acute angle to the annular U-shaped socket or channel portion 11 which is presented in 110

wardly in a plane at right angles to channel 9 to receive the barrel head 15.

In applying the improved heading and binding hoop, the split ring hoop 5, as shown in Fig. 1, is fitted around the circular head member 15 formed of wood or other suitable material, and compressed closely upon the head to cause the ends of the split ring to meet. While the split ring is held tight upon the head in this position, suitable fastening means are applied to secure the compressed ring upon the head. As shown in the drawings, small brads or tacks 12 are driven through the openings 13 of the wall or channel portion 11 into the body of the head 15.

The barrel head with flanged binding hoop secured upon it as described, constitutes a flanged head for the barrel which will fit snugly in the open end of the barrel with the annular channel 9 closely inclosing the barrel chime and forming thereon a strengthening bead to withstand the wear and tear and increase the rigidity of the headed barrel structure. The flanged barrel head can be secured in place upon the barrel by means of nails or brads such as shown at 16, passing through properly prepared openings 17 in the annular flange 6 and inner wall 11 into the body of the head 15. By removing nails 16, the head can readily be taken out of the barrel and preserved for future use.

In Figs. 8, 9, 10 and 11 I have shown slightly modified forms of the improved binding and heading bands applicable to angular closures having flat face walls. In these forms of the invention, each portion of the binding strip has the same general characteristics as the circular form. In Figs. 8 and 9, the binding strip is a continuous band with outer wall 6^a, binding edge 7^a, inner wall 8^a, channel 9^a fitting the top edge of the box 1^a, the inclined wall 10^a and inwardly presented channel portion 11^a inclosing top member 15^a. The binding strip 45 has parts of walls 8^a, 10^a and 11^a cut out to enable strip 6^a to bend neatly around the box corners.

In Figs. 10 and 11, the binding strip is shown in the form of a plurality of short strips, each having walls 6^b, 7^b, 8^b, 10^b and 11^b and the channels for body and top portions of the closures.

I am aware that it has been proposed to secure the heads in closures by certain forms 55 of metal bands, but the heading and binding band of the present invention combines in a

simple practical form the means for securing the band to the head, with the means for fastening the head on the closure and of providing a wearing bead for the exposed 60 walls of the closure. All these features are combined in a strip or band made of a single piece of metal produced by an improved metal bending and shaping process. The inwardly inclined wall 10 is a feature of 65 great practical importance adding great strength to the head securing means. In the event of dropping on end, a package equipped with the improved heading and binding means, it will be observed that any tendency 70 of the head to yield, under pressure of the contents of the closure, will cause the obtuse angle joining walls 8 and 10 to bite into the closure wall and hold the head more securely. 75

I claim:—

1. A closure heading and binding band comprising a single integral piece of sheet metal shaped to form an inwardly presented channel portion to receive a closure head, a downwardly presented channel portion to receive a closure wall, and an inwardly inclined wall joining said channel portions, the walls of the inwardly presented channel portion extending at right angles to the 85 walls of the downwardly presented channel portion.

2. A closure heading and binding band comprising a single integral piece of sheet metal formed with an inwardly presented 90 head-receiving channel portion, a downwardly presented body receiving channel portion, the walls of said channel portions extending at right angles to each other, and an inwardly inclined wall joining said channel portions and forming an acute angle 95 with the former and an obtuse angle with the latter.

3. A barrel heading hoop comprising a split ring formed of a single integral piece 100 of sheet metal with an inwardly presented annular channel portion adapted to engage a barrel head, a downwardly presented annular channel portion adapted to engage the chime of a barrel, an annular rim portion inclosing the outer edge of the barrel chime, and an inwardly inclined wall joining said channel portions, the walls of said channel portions extending at right angles to each other. 105

GEORGE W. SWIFT, JR.
